US0D1003157S

(12) **United States Design Patent** (10) Patent No.: **US D1,003,157 S**
(45) Date of Patent: ** Oct. 31, 2023

(54) **PACKAGING FOR FOODSTUFFS**

(71) Applicant: **Tendentibus Altum B.V.**, Enschede (NL)

(72) Inventor: **René Elenbaas**, Enschede (NL)

(**) Term: **15 Years**

(21) Appl. No.: **35/515,748**

(22) Filed: **Sep. 30, 2022**

(80) **Hague Agreement Data**

Int. Filing Date: **Sep. 30, 2022**

Int. Reg. No.: **DM/225163**

Int. Reg. Date: **Sep. 30, 2022**

Int. Reg. Pub. Date: **Dec. 9, 2022**

(30) **Foreign Application Priority Data**

Apr. 2, 2022 (EM) 008927438-0001

(51) LOC (14) Cl. **01-09**

(52) U.S. Cl.

USPC **D9/430; D9/431**

(58) **Field of Classification Search**

USPC D9/434-436, 499, 414, 420, 421, D9/423-426, 429-433, 455, 456; D3/201, 272

CPC B65D 81/3813; B65D 21/00
